UNITED STATES PATENT OFFICE.

GEORGE H. CARLON, OF OSKALOOSA, IOWA.

WALL-PLUG.

No. 838,007.

Specification of Letters Patent.

Patented Dec. 11, 1906.

Application filed November 10, 1905. Serial No. 286,756.

To all whom it may concern:

Be it known that I, GEORGE H. CARLON, a citizen of the United States, residing at Oskaloosa, in the county of Mahaska and State of Iowa, have invented a new and useful Improvement in a Wall-Plug, of which the following is a specification.

- This invention is an improved construction of wall-plug, the object being to provide a cheap and simple and efficient device which can be arranged between the building-blocks or bricks during the construction of the wall and provide a suitable pocket into which the nail or spike can be driven.
- Another object of the invention is to provide a device of such a character that it can be used in connection with either brick or stone and one that can be used equally as well with artificial or natural stone.
- A still further object is to provide a plug of such a character that when once inserted in the wall all danger of pulling out or working loose is entirely avoided.

With these various objects in view my invention consists, essentially, in constructing a plug from a single piece of thin sheet metal essentially rectangular in form and provided with a lateral extension at its forward portion, which lateral extension is adapted to be folded over and fastened to the main body, thereby providing a pocket, the ends of the plug and extension being provided with flanges which are adapted to be bent in opposite directions, providing flaps for the said pocket, the rear portion of the main plate being adapted to be bent at a right angle, whereby it is adapted to be fit behind the block or brick.

The invention consists also in certain lines of construction hereinafter fully described, and pointed out in the claims.

In the drawings forming a part of this specification, Figure 1 is a perspective view showing the practical application of my invention. Fig. 2 is a detail perspective view of the wall-plug. Fig. 3 is an inverted perspective view of the said plug. Fig. 4 is a sectional view showing the manner of fastening the extension after it has been turned down on the main portion of the plate, and Fig. 5 is a plan view of the block over which the plug is made.

In constructing a wall-plug in accordance with my invention I employ a single piece of suitable sheet metal A, which is cut in the shape indicated in Fig. 5, and which it will

be understood partakes of the shape of an L, consisting of the main portion B and the lateral extension C, the forward ends of the main portion B and lateral extension C being provided with lips or flanges B' and C', respectively, the purpose of which will appear hereinafter.

The lateral extension C is folded upon the line which thereby brings the portion C completely over the forward portion of the part B, and a projecting side C² is folded upon the line 2 and turned under the side edge of the part B, thereby securely fastening the lateral extension C after it has been folded down upon the main portion B. The lips or flanges B' and C' are then bent at right angles to the portions B and C, and consequently project in opposite directions and provide flaps to the pocket D, which is formed between the main portion C, it being understood that this pocket is intended to receive the nail or spike which is to be driven into the wall.

The inner portion of the part B is bent upwardly or downwardly upon the line 4, providing a hook or anchor member B², which is adapted to fit behind the block or brick of the wall, or the said anchor portion can fit into one of the vertical recesses usually formed in concrete blocks.

While I have shown my wall-plug constructed of smooth plate metal, it is obvious that it could be made of corrugated metal, and it will be of course understood that I prefer to make the plug of galvanized metal in order to prevent rust or corrosion.

From the foregoing description, taken in connection with the accompanying drawings, it will be seen that I provide a cheap, simple, and durable construction of wall-plug capable of accomplishing all of the functions hereinbefore enumerated.

Having thus fully described my invention, what I claim as new, and desire to secure by Letters Patent, is—

1. A wall-plug formed from a single plate of metal comprising a main portion having a lateral extension which is folded over and secured to the main portion thereby providing a pocket, the rear end of the main portion being angled, providing an anchor as set forth.

2. A wall-plug formed of a single piece of metal and comprising a main portion having a lateral extension, said lateral extension being adapted to be folded over and fastened to the main portion, the forward ends of the main portion and extension having lips

adapted to be bent in opposite directions, the rear part of the main portion being bent at a right angle thereby providing an anchor as set forth.

- 5 3. A wall-plug formed of a single piece of metal comprising a main portion having lip at the forward end, lateral extension having a lip at the forward end, said extension being adapted to be folded over the main portion,
10 the extending side thereof being adapted to

be bent around the edge of the main portion thereby fastening the extension to said main portion, the rear end of the main portion being bent whereby an anchor is provided as substantially described.

GEORGE H. CARLON.
